UNITED STATES PATENT OFFICE.

PHILIPPE DE CLAMECY, OF CHARLESTOWN, MASSACHUSETTS, ASSIGNOR TO REMINGTON TYPEWRITER COMPANY, OF ILION, NEW YORK, A CORPORATION OF NEW YORK.

TYPE-WRITING MACHINE.

1,266,560.

Specification of Letters Patent. Patented May 21, 1918.

Application filed September 24, 1915. Serial No. 52,384.

To all whom it may concern:

Be it known that I, PHILIPPE DE CLAMECY, a citizen of the Republic of France, and resident of Charlestown, in the county of Suffolk and State of Massachusetts, have invented certain new and useful Improvements in Type-Writing Machines, of which the following is a specification.

My invention relates to typewriting and like machines and the invention, generally stated, may be said to have two main objects in view.

The first main object of the invention, stated broadly, is to provide means by which the machine may be contracted into a smaller space than that which it occupies when in use so that the machine may be readily transported or carried.

As a further feature of this main object of my invention I have constructed the main frame of the machine with relatively movable sections which, when the machine is to be transported, may be moved or folded to inclose the machine and form a case therefor.

The second main object of my invention, generally stated, is to provide a machine in which the noise which ordinarily results from operating it is reduced to a minimum or is entirely eliminated.

To the above and other ends which will hereinafter appear, my invention consists of the features of construction, arrangements of parts and combinations of devices set forth in the following specification and particularly pointed out in the appended claims.

In the accompanying drawings wherein like reference characters indicate corresponding parts in the various views,

Figure 1 is a fragmentary plan view with parts omitted of one form of typewriting machine embodying my invention.

Fig. 2 is an enlarged detail fragmentary view partly in section of the threaded actuating member of one of the type actions and the companion member with which it co-acts.

Fig. 3 is a fragmentary fore and aft vertical sectional view of the machine shown in condition for use.

Fig. 4 is a like sectional view of the machine shown collapsed and the frame closed.

Fig. 5 is a fragmentary detail front view

showing one of the printing keys and some of the associated parts.

Fig. 6 is a fragmentary plan view of one of the keyboard or guide plates and one of the slides by which it is supported.

Fig. 7 is a perspective view of the frame shown closed as it appears when the machine is ready to be transported.

Fig. 8 is a perspective view of the frame as it appears when opened, the machine being omitted in order to more clearly illustrate the construction of the frame.

Fig. 9 is a fragmentary detail transverse sectional view showing the means by which the slides 69 are supported by the member 26.

Fig. 10 is a fragmentary detail perspective view of one of the two-part telescoping rock shafts.

In the various views parts have been omitted to avoid confusion, only so much of the machine being shown as may be necessary to arrive at an understanding of the invention.

In the present instance I have shown my invention embodied in a typewriting machine in which individual type bars are adapted to be impressed at a common center between the top, front face of the platen, each type bar being controlled by a separate key in the keyboard. It should be understood, however, that without diverging from the objects of the invention and the scope thereof as defined in the claims, the invention may be embodied in various styles of typewriting and like keyboard machines.

I will first describe one form of the main frame embodying my invention, it being understood that from certain aspects of the invention it is immaterial what character of typewriting or like machine is employed in connection therewith so long as the fundamental characteristics of this feature of my invention are embodied.

The main frame of the machine may be said to comprise five sections designated respectively by the reference numerals 1, 2, 3, 4 and 5. The section designated as a whole by the reference numeral 1 may be regarded as the main or body portion of the frame and forms a bottom plate and a rear rigidly connected cross plate and carries the other sections that are movable relatively thereto. Thus the section designated as a

- whole by the reference numeral 2 is hinged at 6 to the section 1 and its body portion is adapted to extend in line with the bottom plate of the section 1, as shown in Figs. 3 and 8 when the machine is in use, and to be folded up to the position shown in Figs. 4 and 7 and constitute a front cross plate which incloses the front of the machine. This section 2 is substantially U-shaped in cross section, being provided with rigidly connected side plates 7 which extend at right angles to the plane of the body portion thereof. The section 3 is hinged at one end, as at 8, to the rear cross plate of the section 1. 10 The section 3, when the frame is closed as represented in Fig. 7, constitutes a side plate that incloses the machine at one side thereof. The cover section 4 is hinged at 9 to the side section 3. When the section 3 is opened 15 it is adapted to support the cover section 4 in the thrown back position represented in Fig. 8. In some such position as this the section 4 is adapted to act as a copy holder, the cover section being provided on the inner side thereof with suitable means, such as the spring clips 10, to hold the copy thereon. The section 5 is hinged at 11 to one edge of the cover plate 4 and constitutes a side plate which incloses the side of the machine opposite that which is inclosed by the side plate 3. The plates 3 and 5 are provided with cut-outs 12 in which the side plates 7 of the section 2 are adapted to be received when the casing or frame is closed 20 as represented in Fig. 7. Each of the side plates 3 and 5 is provided with a depending lug 13 adapted to be received in a slot 14 in the section 1. Thus when the section 3 is folded substantially to its closed position 25 the sections 1 and 3 may be sprung away from each other far enough to enable the lug 13 on the section 3 to clear the bottom plate of the section 1 and to receive the associated lug 13 in its opening 14. The lug 30 13 on the plate 5 may be received in its opening 14 when the cover plate is turned down to the closed position. The section 2 is folded up from the position illustrated in Fig. 8 to the position indicated in Fig. 7 35 where the body portion thereof incloses the front of the machine. A suitable spring catch 15 is provided on the cover plate to engage an opening or depression 16 in the section 2 when the parts are closed and thus 40 lock the various sections together in the closed position represented in Fig. 7.
- In Figs. 7 and 8 I have omitted the typewriting machine in order to more clearly illustrate the construction of the casing. It 45 should be understood, however, that the machine is mounted in position on certain of the sections of the casing hereinbefore described and that said sections constitute the frame of the machine and that the machine 50 in its entirety is adapted to be inclosed with-

in the frame or casing when the latter is folded in the condition represented in Fig. 7, and as will be more clearly understood from an inspection of Fig. 4. When, on the other hand, the casing or frame is opened as 70 illustrated in Fig. 8, the machine is adapted to be extended as represented in Fig. 3 when it is in condition for use.

I preferably provide a rubber sheet or plate 17 on the base or bottom plate of the 75 section 1 and another like rubber sheet or plate 18 on the inner side of the section 2. When the casing is opened as represented in Fig. 3 these rubber plates or sheets are aligned and constitute supporting means for 80 the working parts of the typewriting machine in order to reduce or deaden any noise that may be produced thereby. I also preferably provide rubber feet 19 on the bottom of the section 1 and by which it is supported 85 on the table or desk. Rubber feet 20 are likewise provided on the folding section 2 to support the latter in alignment with the bottom plate of the main section.

The type bars or carriers 21 may be of any 90 suitable number and any desired number of types 22 may be employed on each bar, three being shown in the present instance. The type bars are arranged to impress their characters at a common center against the 95 upper, front face of a platen 23 which may be shifted by any suitable means to change the case position thereof. The platen is carried by a suitable carriage supported by the main body portion 1 of the frame. It 100 will be understood that when the frame is opened as shown in Fig. 8, the side plates 3 and 5 are removed from the path of the carriage and offer no obstruction to the travel thereof across the main body portion of the 105 frame and beyond the side edges of the latter. Each type bar is pivoted, as at 24, to a type bar segment 25 mounted on a supporting member 26 adapted to slide fore and aft of the machine toward and away from the 110 platen, as will hereinafter more clearly appear. A type bar shield 27 forms a support for the segment and for a type rest 28. The member 26 extends from side to side of the machine and is supported by the bottom of 115 the section 1 or the rubber plate or sheet 17 thereon. The member 26 is provided with inclosed fore and aft slots 29, as indicated in Fig. 1. Upwardly extending screws, posts or pins 30 are secured to and project upwardly from the bottom plate of the section 1 and are received in the slots 29 in the member 26. Winged screws 31 are threaded on the screws 30 and are adapted to bear against the member 26 and clamp it against the section 1 and thus secure the member 26 in the position to which it may be moved relatively to the bottom of the section 1. There are two screws 30, one at each side of the machine, which are received in the slots 29 and 130

co-act with the walls thereof to guide the plate or section 26 in its movements fore and aft of the machine and to limit such movements of said member when the screws co-act 5 with the ends of the slots.

Each type bar is controlled by a finger key 32 through intermediate actuating connections which, in the present instance, are as follows: Each key has a depending key stem 33 which extends through an aperture in a keyboard or guide plate and is bifurcated at its lower end to receive a crank arm 34 which projects from a member 35 of a two-part rock shaft. This member of the rock shaft 10 in the present instance is cylindrical on its outer surface and is provided with a square bore, as indicated at 36. The forward end of each member 35 receives a bearing in a standard 37 to turn therein around the longitudinal 15 axis of said shaft. Each standard 37 is formed with a slot therein to receive the crank arm 34 of the associated rock shaft, the crank arm being fixed to the member 35 by a drive fit and engaging the side walls of the slot 20 prevents a longitudinal displacement of the member 35 in its bearing on the standard 37. Each standard is pivoted at its lower end, as indicated at 38, to a supporting plate so that each standard is free to receive a slight 25 pivotal movement around a vertical axis. The other member 39 of each two-part shaft is rectangular in cross section where it is received within the square bore of its companion member 35, so that the two parts 30 of the shaft may telescope but are fixed to turn together. Each member 39 is formed with a cylindrical bearing portion 40 received in a standard 41 to support the two-part shaft near the rear end portion thereof. Collars 42 are provided on each side of the standard 40 to prevent a longitudinal displacement of each member 39 with reference to its standard 41. The rear end portion of each member 39 is formed with an internal 45 screw thread, as indicated at 43. An actuating member, designated as a whole by the reference numeral 44, is formed with a thread 45 which co-acts with the internal thread in the associated member 39. The rear end of the member 44 is bifurcated, as indicated at 46, or otherwise formed for effecting a connection with the heel of the associated type bar. In the present instance this connection is effected by a pin 47 which 50 spans the bifurcated portion and is received in a slot 48 in the associated type bar. The lower end of each standard 41 is formed with a contracted bearing portion 49 which is received in a segmental slot 50 formed in the supporting member 26. The under side of the supporting member 26 is undercut or countersunk at 51 to receive a lower head or flange 52 on each of the standards 41. The outline of the countersunk portion 51 is indicated in dotted lines in Fig. 1 from which

it will be seen that it corresponds to the segmental slot 50. Each standard 41 is also provided with an upper flange 53 which is adapted to bear on the upper face of the member 26. In this manner each standard 41 is supported on the member 26 and is adapted to receive a lateral displacement along the slot 50 for purposes which will hereinafter appear.

Each key stem is surrounded by an expansion spring 54 which bears at its upper end against the associated key head and at its lower end against the associated keyboard plate. A depending tubular housing 55 is connected with each key head and surrounds the associated spring 54. Each tubular guide or housing 55 is received and telescopes in a corresponding tubular housing 55^a which is carried by and projects upwardly from the associated keyboard plate. The force of each spring 54 is effective to lift the corresponding key and return the key and the parts controlled thereby to normal position. It should be understood that the lower end of each tubular guide member 55 is adapted to co-act with its associated keyboard plate to limit the depression of the key and thus determine the extent of movement of the parts controlled thereby.

From the foregoing description it will be understood that a depression of each finger key 32 is effective to turn the associated two-part rock shaft 35-39, thus causing the corresponding aligned actuating member 44 to be threaded forwardly along its co-operative member 39 and to move the connected type bar around its pivot 24 to the printing position. When depression on the spring pressed key is released by the operator the associated returning spring 54 is effective to lift the key to its normal position, thereby turning the rock shaft in the opposite direction from that in which it was moved by the key depression. This causes the actuating member 44 to be threaded rearwardly along the member 39 to return the type bar to the normal position shown in Fig. 3. It should be understood that during the operation of the intermediate connections between each type bar and its finger key the actuating member 44 is prevented from turning with the two-part rock shaft by reason of its connection with the associated type bar; whereas the member 39 is held against longitudinal movement by its standard 41 as hereinbefore explained. It will be understood therefore that each type bar is moved to the printing position by a camming action through the threading of one of the members 44 along the other member 39; that the effect of this is to eliminate the whipping action that occurs in ordinary type bar machines. The result that the noise incidental to such a whipping of the type against the platen is eliminated, thus overcoming a dis-

advantage which more than any other is conducive to the production of a noisy machine.

In the present instance I have shown the 5 intermediate connections between the finger keys and the type bars as diverging connections which compensate for the difference in width between the keyboard and the series of type bars, as will be understood from an 10 inspection of Fig. 1. It should be understood that from a certain aspect of this feature of the invention it is immaterial what character of printing instrumentalities and connections are employed so long as the 15 movement of the printing instrumentalities to the printing position is effected by a pressing of the types against the platen by the threading or camming of one member along another in the manner herein disclosed.

In order that the machine may be contracted into a smaller space than that which it occupies when in use, I have combined with the means thus far described, features 25 which enable the keyboard to be contracted and to be moved into the frame of the machine, and which also enable the entire system of type bars to be moved toward the platen as illustrated in Fig. 4. Thus I have 30 provided a series of keyboard or guide plates 56, 57, 58, 59, each of which extends throughout the width of the machine and is received at its ends in grooves 60 in two slides or members 61. The foremost plate 56 is soldered or otherwise fixedly connected to the 35 slides 61, whereas the remaining keyboard plates 57, 58 and 59 are adapted to slide fore and aft of the machine in the grooves 60 of said slides 61 and be guided thereby. 40 Each of the keyboard or guide plates 57, 58 and 59 is substantially U-shaped in cross section to provide flanges 62 which co-act with one another so as to limit the relative sliding movement of the plates with reference 45 one to another. The forward keyboard plate 56 is provided with but one of these flanges 63 for co-operation with the forward flange on the next keyboard plate 57. From an inspection of Fig. 6 it will be understood 50 that the flanges 62 and 63 terminate before the ends of the keyboard plates are reached so that the end of the plates may be properly seated in the guide grooves 60 on the members 61. A corresponding series of supporting plates 64, 65, 66 and 67 is located 55 beneath the keyboard plates hereinbefore described. These plates 64, etc., are formed in substantially the same manner as the keyboard plates and like them are received at their ends in grooves 68 in slides or guide members 69. The forward supporting plate 64 is soldered or otherwise fixedly secured 60 at its ends to the members 69, whereas the other supporting plates 65, 66 and 67 are

adapted to be moved relatively to one another and to the plate 64 and are prevented from moving or being moved away from one another by the flanges 70 thereon which coact with one another in the same manner as the flanges on the keyboard plates. Each keyboard plate carries a row or bank of keys and each supporting plate carries a row of posts or standards 37 for its corresponding row or bank of keys. The forward supporting plate 64 is provided with a finger piece 71 by which the parts may be manipulated to slide the keyboard forward into operative position or slide it rearwardly into the contracted position in the frame of the machine. The slides or guides 60 are disconnected from the frame and are supported in position by the keyboard plates which in turn are supported by a suitable number of connecting posts 72. Each of these posts is secured at its lower end to one of the supporting plates and is threaded at its upper end portion, as indicated at 73, for co-operation with a nut 74 provided with a knurled head 75. Each nut 74 is formed with a circumferential groove 76 which receives the associated plate at a slotted portion thereof, as indicated at 77 (see Fig. 6). In this manner each of the keyboard plates 56 and 59 is engaged by the nuts 74 in such a manner as to cause each of the plates to 9 be elevated or lowered by the adjustment of the associated nuts on their posts 72. A corresponding elevation or lowering of the guides 61 and the remaining keyboard plates will also be effected. In this manner the 100 raising and lowering of the keyboard plates is effective to contract or allow an expansion of the springs 54 in order to vary the force exerted thereby. This results in regulating the "touch" of the keys and in increasing or decreasing the rapidity of restoration of each type action to normal position. In this manner the machine may be adjusted at will to afford an increase or decrease in the speed at which it may be 105 operated.

It will be observed that the rear flange 70 on the supporting plate 67 is made deeper than the others and is adapted to engage the front edge of the supporting member 26, whereas the stop members 78 on the rear ends of the guide members or slides 69 are adapted to co-act with the rear edges of supporting plates 79 secured by screws 80 to the supporting member 26 in order to 115 limit the relative fore and aft sliding movement between the slides 69 and the supporting member 26. The plate-like members 79 are received in the uppermost grooves 68 of the slides 69, as represented in Fig. 9. 120 Thus the guides 69 are supported by the member 26 for sliding movement fore and aft of the machine. The supporting mem-

ber is also, as heretofore pointed out, supported on the bottom plate of the section 1 of the frame. In this manner the support 26 also constitutes a support, through the 5 guides 69, for the supporting plates 64, 65, 66 and 67, these supporting plates and the keyboard plates being united through the posts 72 and the intermediate actuating connections for the associated bank of keys, 10 cause each associated pair of keyboard and supporting plates to travel together in their sliding movements fore and aft of the machine.

The plates 79 are extended forwardly to 15 form arms which terminate in hook-like stops 79^a located forward of the two rear posts 72. It will be understood therefore that after the supporting member 26 is limited in its forward sliding movement by the 20 posts 30 the two rear posts or pins 72 will eventually be brought into engagement with the stops 79^a, which latter will prevent a further forward movement of the supporting plate 67 and its companion keyboard 25 plate 59, preventing a further forward movement of these plates and causing a separation of the keyboard and supporting plates from the contracted relationship shown in Fig. 4 to the extended relation- 30 ship shown in Fig. 3 as will hereinafter more clearly appear. The section 2 of the frame is provided with two upstanding threaded posts 81 which are fixed thereto and with which winged nuts 82 co-act. 35 These threaded posts are adapted to be received in slots 83 in the forward supporting plate 64, as indicated in Figs. 1 and 3. By tightening the nuts 82 at this time the guides 69 are adapted to be clamped firmly 40 against the bottom of the section 2 of the frame, to rigidly connect said guides with the frame and also to prevent the guides 69 and 61 and the parts carried thereby from sliding rearwardly on the guides.

45 When the parts are in the collapsed or contracted position, shown in Fig. 4, and it is desired to move the operating parts of the machine to working positions, the frame is first opened as indicated in Fig. 8. The operator may then grasp the finger piece 71 and move the slides 69 and the parts connected therewith forward on the section 2 of the frame which at this time occupies a position in alinement with the bottom plate of 50 the section 1. The slides 69 and the parts carried thereby may continue to move forwardly until the screws 30 co-act with the rear ends of the slots 29 to effect an arrest of the system of type bars to properly position it with reference to the platen. The 55 slides 69 will continue their forward movement until the stops 78 co-act with the guide 26 or the plate 79 carried thereby, thus arresting further forward movement of the

slides. During this movement of the parts 65 from the positions indicated in Fig. 4 to that represented in Fig. 3 the supporting plates and keyboard plates will be moved relatively to each other into an expanded relation to bring the different rows or banks of 70 finger keys into their proper positions in the keyboard of the machine. This is due to the fact that during the forward movement of the slides 69 and 61 the rear posts 72 were brought into contact with the stops 79^a 75 on the support 26 as hereinbefore explained. The member 26 having been arrested earlier in the forward movement of the slides 69 and 61 by the posts or pins 30 will cause the rear plates 59 and 67 to be held while the 80 remaining plates are pulled forward with the slides until they are more widely separated and assume the positions shown in Fig. 3.

During the forward movement of the 85 slides 61 and 69 the forward members 35 of the two-part telescoping rock shafts will be moved forwardly on their members 39 from the positions indicated in Fig. 4 to those indicated in Fig. 3, thereby lengthening the 90 connection between each finger key and its type bar by a sliding movement of one of the two-part members 35—39 on the other. During this forward movement of the keyboard and the relative movements between the 95 keyboard plates and supporting plates each standard 41 will receive a slight movement along the slot 50 by reason of the change in the angular relations between the different actuating connections of the system. Moreover, the posts or standards 37 will receive a slight pivotal movement on their supporting plates around the pivots 38 by which they are connected to the supporting plates. It should be understood that there is sufficient play between the member 46 of each type action and the type bar, and between each key stem and the crank arm 100 34 to which it is connected, to enable this change in the angular relation between the two-part rock shafts, etc., to be effected. This change in the angular position of each of the two-part rock shafts is indicated diagrammatically in Fig. 1, it being understood that as the single key illustrated at the 105 right hand side of the machine is moved from some such position as that shown in dotted lines to the full line position, the two-part shaft and the actuating device connected therewith will swing around the point of the connection between the actuator 44 and type bar and will assume the full line position shown. When the keyboard has been moved to operative position as shown in Fig. 3 the thumb nuts 82 and 31 110 may be tightened, thus firmly uniting the sections 1 and 2 and rigidly connecting the type bar support 26 to the section 1 of the

frame. Of course the tightening of the screws 82 is also effective to prevent the supporting plates, keyboard plates and slides 61 and 69 from sliding rearwardly into the frame. It will be observed that each end plate 7 is also provided with thumb screws 84, the inner ends of which are adapted to bear against the guides 61 in order to firmly secure the latter relatively to the section 2 of the frame after the desired adjustment of the springs has been effected with the aid of the nuts 74. In this manner the various parts of the keyboard are maintained in their expanded relation and a rigid connection 15 is formed between the various keyboard plates and the frame of the machine.

In order to effect a contraction of the machine so that it may be reduced to a smaller compass and inclosed within the frame and 20 thus facilitate carrying or transporting the machine, it is merely necessary to loosen the screws 82, 31 and 84 and slide the keyboard rearwardly into the body portion 1 of the frame with the aid of the finger piece 71. 25 This also effects a contraction in relationship between the keys and moves the type bars toward the platen as shown in Fig. 4.

The rearward displacement of the slides 61 and 69 to effect the above mentioned contraction of the parts results in moving the keyboard and supporting plates rearwardly with the slides until the plate 67 abuts the supporting member 26. The member 26 together with the parts carried thereby is then 35 taken up and moved toward the platen until the supporting member is arrested by the posts or pins 30. A further rearward movement of the slides causes the supporting and keyboard plates to be moved relatively one 40 to another until further movement of the overlapping plates is prevented when the parts as a whole will assume the contracted relationship shown in Fig. 4, the different banks of keys having been moved into a 45 more compact relationship. Of course it will be understood that during the shifting and contraction of the keyboard in the manner specified, the members 39 of the two-part shafts will be telescoped within their 50 companion members so as to effect a shortening of the connections between the finger keys and type bars. The casing or frame may then be closed in the manner hereinbefore pointed out and as shown in Fig. 7.

55 Inasmuch as the keyboard in its entirety, in the present construction, may be moved bodily into the frame of the machine, it is not so essential to provide as great a contraction of the keyboard as otherwise might 60 be deemed necessary.

It will be understood that the actuating member 44 of each type action is aligned with the companion member 39 and that during the actuation of the key an axial movement

of one of these members along the other is 65 effected to provide a lengthening or shortening of the two-part member which results in the actuation of the associated type bar. It will also be understood that this axial movement of each actuating member 44 to 70 operate a type bar is produced by a turning movement of the associated two-part rock shaft alined therewith and controlled by the associated finger key.

From the foregoing description it will be 75 understood that each socket in which the threaded spindle or actuating member 44 is received constitutes an internally threaded sleeve which in the operation of the machine is free to rotate but is held against axial 80 movement; that each sleeve constitutes one member of a two-part threaded connection, the other member being the threaded spindle 44; that these members are alined and one of them has a telescoping movement in the 85 other, thus effecting a lengthening or shortening of the two-part connection; that this lengthening or shortening of the connection, or the telescoping movement of one member in the other controls the printing movement 90 of the associated type bar; that a rotative movement of one of these members is effective to produce a rectilinear or axial movement of the other alined member to control the printing movement of the bar; and that 95 the printing stroke of each bar is controlled by a spiral cam which impresses the type against the platen.

It will also be seen that while the keys of each bank are maintained by the keyboard 100 plate thereof fixed relatively to one another when the machine is collapsed, the keys of the different banks may be brought into contracted relationship.

It should be understood that suitable 105 means may be provided for shifting the platen, for spacing the carriage, etc. If desired, keys for controlling such means may be carried by the foremost keyboard and supporting plates 56 and 64, respectively, 110 and these keys may, if desired, be connected to their respective means by connections such as are employed for the printing keys so as not to interfere with the collapsing of the keyboard and its movement into the 115 body portion of the frame. I have not shown the means in question but have merely illustrated a space key 32^a, it being understood that this key may be connected like the printing keys to control suitable 120 escapement mechanism for the carriage.

By adjusting the actuating members 44 relatively to the sleeves in which they are received before the members 44 are connected with the type bars, or by turning the 125 members 39 more or less with reference to the members 35 before said members 35 and 39 are connected, a shortening or lengthen-

ing of the connections between the finger keys and type bars may be effected to regulate the impression of the types on the platen or the force which may be applied to each 5 type at the depression of its finger key.

While I have described with considerable detail one form of mechanism embodying the main features of my invention, it should be understood that the construction shown is 10 merely illustrative of one of the various forms of mechanism in which the invention may be clothed and that various modifications may be made without departing from the spirit and scope of my invention and 15 that certain features of the invention may be used without others.

What I claim as new and desire to secure by Letters Patent, is:—

1. In a portable keyboard machine of the 20 character specified, a keyboard, and means which enable said keyboard to be contracted or expanded at will.

2. The combination of a series of type bars, a series of finger keys, and separate 25 and distinct actuating connections between each finger key and its type bar, said connections including means that enable said keys to be moved from their operative positions into the frame of the machine and 30 thereby reduce the dimensions of the machine.

3. The combination of printing instrumentalities; a series of keys therefor forming a keyboard; and means which enable a 35 contraction of the keyboard to be effected, said means comprising two-part rock shafts intermediate the finger keys and printing instrumentalities and one member of each of 40 which shafts is adapted to be moved relatively to its companion part.

4. In a keyboard machine of the character specified, the combination with the keys of the keyboard, of means which enable the keyboard to be shifted into the main frame 45 of the machine and also enable the keys to receive a relative shifting movement in order to contract the keyboard into smaller compass.

5. In a machine of the character specified, 50 the combination with a main frame on which working parts of the machine are mounted and which comprises sections adapted to be folded relatively to one another, of means which enable certain of said working parts 55 to be shifted relatively to and free of certain of said sections and enable the latter to be folded and to inclose the entire machine.

6. In a machine of the character specified, 60 the combination of a keyboard consisting of a plurality of rows of keys; and means which enables the keys of said keyboard to be moved into and out of operative position,

said means comprising guide plates for said keys, and means which enable said guide 65 plates to slide into and out of operative position in the keyboard and to carry the keys with them.

7. In a machine of the character specified, the combination of a series of finger keys 70 which form a keyboard; and means which enable said keys to be moved into a contracted relationship, said means comprising a series of keyboard plates to which said keys are operatively connected and which 75 are movable relatively to each other in overlapping relation to contract the keyboard.

8. The combination of printing instrumentalities, a series of keys therefor forming a keyboard, means which enable a contraction of the keyboard to be effected, and 80 means operative by a single movement to effect such contraction of the keyboard.

9. The combination of a series of type bars, a series of finger keys, and separate 85 and distinct actuating connections between each finger key and its type bar, said connections including means that enable said keys to receive a sliding movement from their operative positions into the frame of 90 the machine and thereby reduce the dimensions of the machine.

10. The combination of printing instrumentalities, and two-part key actuated rock-shafts therefor, one member of each key actuated rock shaft being connected with a key and being movable on its companion member to enable the keys to be moved from their operative positions in the keyboard of the machine into a contracted relationship. 100

11. In a keyboard machine of the character specified, the combination with the keys of the keyboard, of means which enable the keyboard to be shifted by a sliding movement into the main frame of the machine 105 and also enable the keys to receive a relative sliding movement in order to contract the keyboard into smaller compass.

12. In a machine of the character specified, the combination with a main frame on 110 which working parts of the machine are mounted and which comprises sections adapted to be folded relatively to one another, of means which enable certain of said working parts to receive a sliding movement 115 relatively to the frame and the machine to be contracted within a smaller space than it occupies when in use and to be entirely inclosed within said frame.

13. In a machine of the character specified, the combination of a keyboard in which the keys are arranged in banks; and means which enable said keys to be moved into and out of operative position, said means comprising guide plates one for each bank of 125 keys, and means which enable the guide

- plates to be moved relatively to one another and to carry the keys with them and contract the keyboard.
14. In a machine having a keyboard comprising a plurality of rows of keys, the combination of printing instrumentalities controlled by keys in the keyboard of the machine, and means which enable said keyboard to be collapsed.
15. In a machine of the character specified, the combination with a main frame on which working parts of the machine are mounted and which comprises sections adapted to be folded relatively to one another, of means which enable working parts of the machine to be shifted independently of the frame from their operative positions into the main body portion of the frame and to be inclosed by the foldable sections of the frame.
16. In a machine of the character specified, the combination of a keyboard; and means which enable the keys of said keyboard to be moved into and out of operative position, said means comprising guide plates for said keys, slides on which said guide plates are mounted, and means which enable the slides to move on the frame of the machine.
17. In a machine of the character specified, the combination of a series of finger keys which form a keyboard; and means which enable said keys to be moved into a contracted relationship, said means comprising a series of keyboard plates to which said keys are operatively connected and which are movable relatively to each other in overlapping relation to contract the keyboard, and means for limiting the movements of said plates relatively to the frame of the machine.
18. The combination of printing instrumentalities, keys therefor, and a two-part actuating device between each of said keys and a printing instrumentality, one member of each of said two-part devices having a sliding connection with its other member that enables the associated key to be moved close to the body of the machine and contract the keyboard.
19. The combination of printing instrumentalities, keys therefor, and a two-part actuating rock shaft between each of said keys and a printing instrumentality, one member of each of said two-part rock shafts having a sliding connection with its other member that enables the keys to be shifted from their operative positions in the keyboard to an inoperative position.
20. In a machine of the character specified, the combination with a main frame on which working parts of the machine are mounted and which comprises sections adapted to be folded relatively one to another, of means which enable working parts of the machine to slide one on another into a contracted relationship within said frame and enable the machine as a whole to be inclosed within the frame.
21. In a machine of the character specified, the combination of a keyboard in which the keys are arranged in banks; and means which enable said keys to be moved into and out of operative position, said means comprising guide plates one for each bank of keys, means which enable the guide plates to be moved relatively to one another and to carry the keys with them and contract the keyboard, and means which limit the movements of the guide plates relatively to one another.
22. In a keyboard machine of the character specified, the combination of a series of finger keys which form a keyboard; and means which enable said keys to be moved into a contracted relationship, said means comprising a series of co-acting keyboard plates which are substantially U-shaped in cross section and are movable a limited distance relatively to one another to contract the keyboard, and means for limiting the movements of said plates relatively to the frame of the machine.
23. The combination of printing instrumentalities, a series of keys therefor forming a keyboard, means which enable a contraction of the keyboard to be effected, and means operative by a single movement in one direction to effect such contraction of the keyboard and operative to effect an expansion of the keyboard by a single movement in the opposite direction.
24. In a typewriting machine, the combination of type bars; finger keys; and intermediate actuating devices between each of said keys and the associated type bar, the said actuating devices between each finger key and type bar including a telescoping rock shaft.
25. In a keyboard machine of the character specified, the combination with a main frame on which working parts of the machine are mounted and which comprises hinged cover side and front sections, of means which enable said hinged sections to be closed and with the remaining portions of the frame to entirely inclose the machine within said frame, said means including means which enable the keyboard to be moved into the frame independently of its hinged sections.
26. In a machine of the character specified, the combination of a keyboard; and means which enable the keys of said keyboard to be moved into and out of operative position, said means comprising guide plates for said keys, means which enable said guide plates to slide into and out of operative position in the keyboard and to carry the keys with them, and means which limit the slid-

ing movements of said guide plates relatively to the frame of the machine.

27. In a keyboard machine of the character specified, the combination of a series of 5 finger keys which form a keyboard; and means which enable said keys to be moved into a contracted relationship, said means comprising a series of keyboard plates to which said keys are operatively connected 10 and which are movable relatively to each other in overlapping relation to contract the keyboard, and guides on which said keyboard plates are adapted to slide.

28. In a machine of the character specified having a keyboard, consisting of a plurality of banks of keys, the combination of 15 printing instrumentalities controlled by keys in the keyboard of the machine, and means which enable said keys to be moved 20 fore and aft of the machine from the positions they occupy in the different banks to a position close to the front of the machine.

29. In a typewriting machine, the combination of printing instrumentalities, a plurality of banks of finger keys therefor which 25 form a keyboard, and means which enable the keys to be moved into a contracted relationship and to be moved into the frame of the machine and thus eliminate the key- 30 board.

30. In a machine of the character specified, a main frame which supports the working parts of the machine, said frame comprising sections movable relatively to one 35 another and adapted to inclose the machine, one of said sections constituting a cover when closed and a copy holder when open.

31. In a machine of the character specified, the combination of a keyboard; and 40 means which enable the keys of said keyboard to be moved into and out of operative position, said means comprising guide plates for said keys, slides on which said guide plates are mounted, means which enable the 45 slides to move on the frame of the machine, and means for securing said slides against movement.

32. In a keyboard machine of the character specified, the combination of a series of 50 finger keys which form a keyboard; and means which enable said keys to be moved into a contracted relationship, said means comprising a series of keyboard plates to which said keys are operatively connected 55 and which are movable relatively to each other in overlapping relation to contract the keyboard, guides on which said keyboard plates are adapted to slide, and means for supporting said guides for sliding movement relatively to the frame of the machine 60 and for limiting them in such movements.

33. In a machine of the character specified having a keyboard comprising a plurality of rows of keys, the combination of 65 printing instrumentalities controlled by

keys in the keyboard of the machine, and means which enable said keyboard to be contracted into a smaller space than it occupies when in use.

34. In a typewriting machine, the combination of printing instrumentalities, finger keys therefor arranged in banks, means which maintain the keys of each bank in a fixed relationship but which enable the keys of different banks to be brought into a contracted relationship. 70

35. The combination with printing keys and a space key, of means which enable said keys at a single operation to be given a rectilinear movement from their respective 80 positions in the keyboard to a compact position close to the frame of the machine.

36. In a machine provided with a keyboard comprising printing keys in a plurality of rows, the combination of the main 85 frame which supports the working parts of the machine, and means for enabling the keyboard to receive a fore and aft rectilinear movement and to be brought within said frame. 90

37. In a machine of the character specified provided with a keyboard, the combination of the main frame which supports the working parts of the machine, said frame having a hinged section which extends beneath the keyboard when the machine is in use, and means which enable the keyboard to be shifted independently of said hinged section to a position within the frame and which enable the said hinged section to be 95 moved to an inclosing position. 100

38. In a typewriting machine, the combination of a printing instrumentality, and key actuated means for moving the same to the printing position, said means including 105 a screw by which movement of the printing instrumentality to printing position is effected; said screw in operation being fixed against axial movement.

39. In a typewriting machine, the combination of a printing instrumentality; a finger key therefor; intermediate actuating connections between said finger key and printing instrumentality which include members united by a threaded connection and effect a movement of the printing instrumentality to printing position by threading one of said members on the other, and means for moving said key into and out of 110 operative position in the keyboard. 115

40. In a typewriting machine, the combination of a printing instrumentality, a threaded member, a key for turning said member, and means controlled by the turning action of said threaded member for moving 120 said printing instrumentality to printing position. 125

41. In a typewriting machine, the combination of a printing instrumentality, and key actuated means for moving the same to 130

the printing position, said means including a screw by which movement of the printing instrumentality to printing position is effected, and a sliding connection between said key and screw that enables the key to be moved from its operative position in the keyboard toward the body of the machine and thus reduce the compass of the machine.

42. In a typewriting machine, the combination of a two-part threaded member, key controlled means for turning one of said members relatively to the other and thus produce a movement of one of said members along the other, and a printing instrumentality controlled in its approach to the printing position by said last mentioned movement.

43. In a typewriting machine, the combination of a series of finger keys; a series of type bars; and intermediate connections between each type bar and its finger key, said connections including a two-part threaded member, one part of which is turned by the associated key and the other part of which is connected to the associated type bar and receives a movement along the first mentioned part to actuate the type bar, and a sliding connection between the key and the said part that is turned thereby and by which the key may be moved from its operative position in the keyboard.

44. In a typewriting machine, the combination of a spiral cam which in action is fixed against axial movement but is adapted to be turned, a key for controlling the turning movement of said cam, a printing instrumentality, and means controlled by the turning movement of said spiral cam for controlling the printing movement of said printing instrumentality to printing position.

45. In a typewriting machine, the combination of a type carrier, an actuating member connected with said type carrier, a key actuated rock shaft, a threaded connection between said rock shaft and actuating member and by which a relative threading between the actuating member and rock shaft is produced by the turning movement of the rock shaft and a printing movement of the type bar is effected, and a sliding connection between the key and said rock shaft, said sliding connection enabling the key to be moved from its operative position in the keyboard into a contracted relationship.

46. In a typewriting machine, the combination of a series of type bars, a separate screw controlling the movement of each type bar to printing position, each of said screws being fixed against axial movement, and key actuated means for controlling said screws.

47. In a typewriting machine, the combination of a series of type bars; and individual means for moving each of said type

bars to the printing position, said means for each type bar comprising a threaded sleeve free to rotate but held against axial movement, a screw received in said sleeve and which is movable axially therein but is held against turning movement, a connection between said screw and the associated type bar so that an axial movement of the screw will move the associated type bar to the printing position, key controlled means for turning said sleeve, and a sliding connection between said key and sleeve.

48. In a typewriting machine, the combination of a series of finger keys; a series of type bars; and intermediate connections between each type bar and its finger key, said connections including a two-part threaded member, one part of which is turned by the associated key and the other part of which is connected to the associated type bar and receives a movement along the first mentioned part to actuate the type bar.

49. In a typewriting machine, the combination of a type carrier; and means for moving the type carrier to printing position, said means including two members operatively connected by a threaded connection, and means for threading one of said members along the other and thereby moving the type carrier to the printing position, said last mentioned means comprising a key and a sliding connection between said key and one of said members.

50. In a typewriting machine, the combination of a printing instrumentality, actuating means therefor separate and distinct from said printing instrumentality but operatively connected therewith, said actuating means including a two-part member the parts of which are united by a threaded connection and which is lengthened and shortened by a threading of one part on the other in order to control the movement of the printing instrumentality, and a key for controlling the lengthening and shortening of said two-part member.

51. In a typewriting machine, the combination of a series of type bars; and actuating means for said type bars, the actuating means for each type bar comprising a separate two-part member the parts of which are united by a threaded connection and which is lengthened and shortened by a threading of one of said members on the other in order to control the movement of the associated type bar to and from the printing position, and a separate key for controlling the lengthening and shortening of each of said two-part members.

52. In a typewriting machine, the combination of a type carrier; and means for effecting a printing movement of said type carrier, said means comprising a two-part connection including two telescoping mem-

bers one of which has a rectilinear telescoping movement on the other that effects a variation in the length of said connection, means which enable such variation in the length of said connection to effect a printing movement of the type carrier, and a key for controlling such telescoping movement.

53. In a typewriting machine, the combination of a series of type bars; and individual means for effecting a printing movement of each of said type bars, said individual means for each type bar comprising a two-part connection including two telescoping members one of which has a rectilinear telescoping movement on the other that effects a variation in the length of said connection, means which enable such variation in the length of said connection to effect a printing movement of the associated type bar, and a key for each pair of telescoping members for controlling the telescoping movement thereof.

54. In a typewriting machine, the combination of a series of type bars; and individual means for effecting a printing movement of each of said type bars, said individual means for each type bar comprising a two-part connection including two telescoping members one of which has a rectilinear telescoping movement on the other that effects a variation in the length of said connection, means which enable such variation in the length of said connection to effect a printing movement of the associated type bar, a threaded connection between each pair of telescoping members and by which the telescoping movement of the latter is effected by a relative turning movement between said members and a key for controlling the relative turning movement of said members, thereby controlling the threading of one of said members on the other.

55. In a typewriting machine, the combination of a type carrier, an actuating member connected with said type carrier, a key actuated rock shaft, and a threaded connection between said rock shaft and an actuating member and by which a relative threading between the actuating member and rock shaft is produced by the turning movement of the rock shaft and a printing movement of the type bar is effected.

56. In a typewriting machine, the combination of a type carrier; and means for moving said type carrier to the printing position, said means comprising two members one of which is adapted to move along the other to effect a printing movement of the type carrier, means by which such movement of one of said members along the other is controlled by a turning movement of one of said members on its longitudinal axis and relatively to the other member,

and key controlled means for controlling the relative turning movement between said members.

57. In a typewriting machine, the combination of a series of type bars; and individual actuating means for each of said type bars, the individual actuating means for each type bar comprising two members one of which is adapted to move along the other to effect a printing movement of the associated type bar, means by which a movement of one of said members along the other associated member is controlled by a turning movement of one of the companion members around its longitudinal axis relatively to the other member, and key controlled means for controlling the said relative turning movement between the companion members.

58. In a typewriting machine, the combination of a type carrier; and means for moving said type carrier to the printing position, said means comprising a two-part connection including a threaded sleeve, and a screw received in said threaded sleeve and enabling a lengthening and shortening of the two-part connection to be effected, one of said screw and sleeve members being operatively connected to the type bar, and key controlled means for effecting a relative turning movement of said members and thereby effecting a threading of one of said members along the other to actuate the type carrier.

59. In a typewriting machine, the combination of a type carrier; and means for moving said type carrier to the printing position, said means comprising a threaded sleeve free to rotate but held against axial movement, a screw received in said sleeve and which is movable axially therein but is held against turning movement, a connection between said screw and type carrier so that an axial movement of the screw will move the type carrier to printing position, and key controlled means for turning said sleeve.

60. In a typewriting machine, the combination of a series of type bars; and individual means for moving each of said type bars to the printing position, said means for each type bar comprising a threaded sleeve free to rotate but held against axial movement, a screw received in said sleeve and which is movable axially therein but is held against turning movement, a connection between said screw and the associated type bar so that an axial movement of the screw will move the associated type bar to the printing position, and key controlled means for turning said sleeve.

61. In a typewriting machine, the combination of a type carrier; and means for moving the type carrier to printing position, said means including two members

- operatively connected by a threaded connection, and means for threading in a straight line one of said members along the other by effecting a relative turning movement of 5 said members and thereby moving the type carrier to the printing position wholly by said straight line movement.
62. In a typewriting machine, the combination of a series of type bars; and individual means for moving each of said type bars to the printing position, said means for each type bar including two members operatively connected by a threaded connection, and means for threading one of said members along the other in a straight line by a relative turning movement of said members and thereby moving the associated type bar to the printing position wholly by said straight line movement.
63. In a typewriting machine, the combination of a type carrier; and means for camming said type carrier to the printing position, said means including a spiral cam fixed against axial movement, a device that co-acts therewith, and key controlled means for effecting a relative movement between said cam and its co-acting device to cam the type carrier to the printing position.
64. In a typewriting machine, the combination of a series of type bars; and individual means for camming each of said type bars to the printing position, said means for each type bar comprising a spiral cam fixed against axial movement and operatively connected to the associated type bar, a co-acting device, and key controlled means for effecting a relative movement between said cam and its co-acting device to cam the associated type bar to the printing position.
65. In a typewriting machine, the combination of a type bar, an axially movable spindle connected therewith, a sleeve which is fixed against axial movement but is free to be turned, a threaded connection between said sleeve and spindle, and a key controlled rock shaft for turning said sleeve.
66. In a typewriting machine, the combination of a type carrier, an axially movable member connected with said type carrier, a second member alined with said first mentioned member but fixed against axial movement, a threaded connection between said members, and key controlled means co-operative with one of said members to effect a threading of the first mentioned member along the second member and thus move the type carrier to the printing position.
67. In a typewriting machine, the combination of a type carrier, an axially movable member connected with said type carrier, a second member alined with said first mentioned member but fixed against axial movement, a threaded connection between said members, and a key controlled rock shaft 5 operatively connected to one of said mem-
- bers to turn it and thereby effect a threading of the first mentioned member along the second member and thereby move the type carrier to the printing position.
68. In a typewriting machine, the combination of a pivoted type bar, two actuating members therefor arranged end to end, key controlled means for effecting a relative rotative movement between said actuating members, and means for rendering said relative rotative movement between said members operative to effect a rectilinear movement of one of them and to move the type bar to the printing position wholly by said rectilinear movement.
69. In a typewriting machine, the combination of a series of type bars; and individual actuating means for each of said type bars comprising an axially movable threaded spindle connected to the associated type bar, a threaded sleeve co-operative with said spindle and fixed against axial movement but free to be turned to effect an axial movement of the spindle along said sleeve, and a key controlled rock shaft for turning said sleeve.
70. The combination of printing keys, stems therefor, coiled returning springs surrounding said stems and co-operative at their upper ends with the keys, and adjustable means co-operating with the lower ends of a plurality of said springs.
71. The combination of a series of printing keys, a keyboard plate, returning springs interposed between and bearing against said keys and said plate, and means for adjusting said plate relatively to said keys.
72. The combination of a series of printing keys, a series of keyboard plates, returning springs interposed between said keys and said plates, and means for simultaneously adjusting a plurality of said keyboard plates relatively to said keys to vary the force exerted by said springs.
73. The combination of a series of printing keys, a series of keyboard plates, returning springs interposed between said keys and said plates, means for simultaneously adjusting a plurality of said keyboard plates relatively to said keys to vary the force exerted by said springs, and means which enable said plates to be moved relatively to one another in an overlapping relation.
74. The combination of a series of finger keys which form a keyboard; and means which enable said keys to be moved into a contracted relationship, said means comprising a series of co-acting keyboard plates which are substantially U-shaped in cross section and are movable a limited distance relatively to one another to contract the keyboard.
75. In a typewriting machine, a keyboard comprising a plurality of rows of keys, and means for bringing said rows of keys closer

together than they are when in normal working positions.

76. The combination with a plurality of independently operable printing instrumentalities, a plurality of rows of printing keys, intermediate connections between said keys and said printing instrumentalities, means for condensing said rows of keys, and means for condensing said connections between said keys and said printing instrumentalities.

77. In a typewriting machine, the combination of type carriers; a keyboard therefor; a platen; and means which enable the machine to be contracted into a smaller space than that which it occupies when in use, said means comprising means which enable the type carriers and platen to be adjusted bodily relatively to each other into and out of coöperative relation and enable the keyboard to be shifted bodily into and out of operative position.

78. In a typewriting machine, the combination of type carriers; a keyboard therefor; a platen; and means which enable the machine to be contracted into a smaller space than that which it occupies when in use, said means comprising means which enable the keyboard and type carriers to be adjusted bodily relatively one to the other and enable both to be adjusted bodily relatively to the platen.

79. In a typewriting machine, the combination of type carriers; a keyboard therefor; a platen; and means which enable the machine to be contracted into a smaller space than that which it occupies when in use, said means comprising means which enable the keyboard to be contracted and a relative bodily adjustment into and out of operative position to be effected between the type carriers and platen.

80. In a typewriting machine, the combination of type carriers; a keyboard therefor; a platen; and means which enable the machine to be contracted into a smaller space than that which it occupies when in use, said means comprising means which enable the keyboard to be contracted and also to be moved bodily relatively to the type carriers and also which enable the type carriers to be adjusted bodily into and out of coöperative relation with and relatively to the platen.

81. In a typewriting machine, the combination of type carriers; a keyboard therefor; a platen; and means which enable the machine to be contracted into a smaller space than that which it occupies when in use, said means comprising a frame having relatively movable sections within which the working parts of the machine are adapted to be received, and means which enable the type carriers and platen to be adjusted bodily relatively one to the other into and out of coöperative relation.

82. In a typewriting machine, the combi-

nation of type actions; a platen; and means which enable the machine to be contracted into a smaller space than that which it occupies when in use, said means comprising means which enable every part of each type action to be adjusted bodily relatively to the platen, the type carriers being adjusted into and out of coöperative relation with the platen.

83. In a typewriting machine, the combination of type actions; a platen; and means which enable the machine to be contracted into a smaller space than that which it occupies when in use, said means comprising means which enable parts of each type action to be adjusted relatively one to another and to be brought into a contracted relationship and enable every part of each type action to be adjusted bodily relatively to the platen, the type carriers being adjusted into and out of coöperative relation with the platen.

84. In a typewriting machine, the combination of a support, a platen carriage, type, and a standard keyboard slidably mounted to move bodily as a unit from a normal open position to a compact position and operatively connected to the type.

85. In a typewriting machine, the combination of a support, a carriage, type, and a non-pivoted standard keyboard mounted to move bodily as a unit from a normal open position to a compact position and operatively connected to the type.

86. In a typewriting machine, the combination of a substantially box-like main member, a keyboard supporting member horizontally movable into the main member, type, a platen carriage, key-operated levers mounted upon the keyboard member and forming a part of a standard keyboard and operatively connected to the type, and means adapted to hold the keyboard member in an open extended position or permit said member to be forced inward.

87. In a typewriting machine, the combination of a support, a platen, a keyboard, printing instrumentalities operated by keys of said keyboard, and means which enable the keyboard to be extended or to be moved to a compact position, said means comprising slides.

88. In a typewriting machine, the combination of a support, a platen, a keyboard, printing instrumentalities operated by keys of said keyboard, and means which enable the keyboard to be extended or to be moved to a compact position, said means comprising telescoping members adapted to slide one on another.

89. In a typewriting machine, the combination of a support, type, and a slidable keyboard mounted to move from the normal position of use to a compact position with reference to said support, keys of the key-

board having operative connection with the type through members movable relatively one to another during the movement of the keyboard.

5. 90. In a typewriting machine, the combination of a main support, a horizontally slidable member movable relatively thereto, types, finger keys, and operative connections between said finger keys and said types, 10 said connections comprising key-controlled devices carried by said slidable member and movable relatively to certain other members of said connections to enable the keyboard to be moved from its position of use to a 15 compact position with reference to said main support.

91. In a typewriting machine, the combination of a support comprising a relatively fixed main member, a horizontally slidable 20 member adapted to move into the main member from an extended position to a compact one relatively to said main member, type bars, and keys carried by the horizontally slidable member, said keys being operatively 25 connected to the type bars and adapted to be moved to an extended or a compact position without operating the type bars.

92. In a typewriting machine, the combination of a main supporting member, a horizontally 30 sliding member adapted to be moved toward the main member to make the machine compact, key-operated devices carried by said slidable member and forming part of a key-board, a spacing key also carried 35 by said slidable member, type, and operative connections between said key-operated devices and the type.

93. In a typewriting machine, the combination of a main member, a keyboard carrying member horizontally movable from a position where it extends outside of said main member to a position where it is contained within the main member, type, key operated devices carried by said keyboard member 45 and operatively connected to the type, and releasable means operative to hold the said keyboard member in its extended position or permit said member to be forced into the main member.

50. 94. In a typewriting machine, the combination of type bars, keys for controlling said type bars, and means for reducing the dimensions of the machine, said means comprising a key support, means for supporting said key support, and a tongue and groove connection between said key support and the means by which it is supported, whereby the key support with the keys supported thereby may receive a movement toward and from the rear of the machine.

95. In a typewriting machine, the combination of a support comprising a slidable member and a relatively fixed member, type movable rearwardly for printing purposes, 65 a keyboard including key operated devices

and a space key carried by said slidable member of the support, and operative connections between said devices and the type and relatively to which the devices are moved during the movement of the keys and devices with said slidable member.

96. In a typewriting machine, the combination of a support comprising a slidable member and a relatively fixed member, type bars movable rearwardly for printing purposes, a keyboard including key-operated devices carried by said slidable member of the support and movable therewith into said fixed member, and operative connections between said devices and the type bars and relatively to which the devices are moved during the movement of the keys and devices with said slidable member.

97. In a typewriting machine, the combination of a support comprising relatively fixed and slidable members, type, a keyboard comprising printing keys and a space key carried by a slidable member of said support and movable therewith, and operative connections between said printing keys and the type comprising means that afford a relative movement between co-acting members of said connections during the sliding movement of said slidable member.

98. In a compactible typewriting machine, the combination of a support, a platen, a series of type bars, a keyboard mounted for movement from a compacted position to an extended position and vice versa, separate and distinct connections between each printing key of the keyboard and the type bar, and means whereby the act of moving the keyboard to extended position automatically changes the distance between the type bars and platen.

99. In a typewriting machine, the combination of printing instrumentalities, keys therefor mounted for movement into and out of compact position with reference to the main body portion of the frame of the machine, a platen, and means whereby the movement of the keys to extended position automatically changes the relation between the printing instrumentalities and platen.

100. In a typewriting machine, the combination of printing instrumentalities, keys therefor mounted for movement into and out of compact relation, a platen, and means for affording a relative bodily movement between the printing instrumentalities and platen into and out of compact relation.

101. In a typewriting machine, the combination of printing instrumentalities, keys therefor mounted for movement into and out of compact relation, a platen, means for affording a relative bodily movement between the printing instrumentalities and platen into and out of compact relation, and means by which a relative bodily movement between the printing instrumentalities

and platen into compact relation is automatically effected when the keys are moved into compact relation.

102. In a typewriting machine, the combination of a platen, printing instrumentalities, keys therefor, means for affording a relative movement between said keys and the printing instrumentalities into compact relation, and means for affording a relative movement between the printing instrumentalities and the platen into compact relation.

103. In a typewriting machine, the combination of a platen, printing instrumentalities, keys therefor, means for affording a relative movement between said keys and printing instrumentalities into and out of compact relation, means for affording a relative movement between the printing instrumentalities and platen into and out of compact relation, and means whereby the relative movement of the keys and printing instrumentalities out of compact relation is operative to automatically effect a relative movement between the printing instrumentalities and platen out of compact relation.

104. In a typewriting machine, the combination of printing instrumentalities; a platen; and means which enable the machine to be contracted into a smaller space than that which it occupies when in use, said means comprising means whereby the printing instrumentalities may be adjusted by moving them relatively to and into and out of coöperative relation with said platen when the latter is at rest.

105. The combination of printing instrumentalities and two-part key-actuated devices therefor, one member of each key actuated device carrying a key and being movable on its companion member to enable the keys to be moved relatively one to another from their operative positions in the keyboard into a contracted relationship.

106. In a typewriting or like machine, the combination of printing instrumentalities, a key-board, the keys of which control said printing instrumentalities, and means which enable the keys of the keyboard to be moved relatively one to another into a contracted relationship nearer to the rear of the machine than when said keys are in position for use.

107. The combination with the main portion of the frame of the machine, key carrying members movable from their respective positions in the keyboard into the main portion of the frame to reduce the dimensions of the machine, and a movable transverse bar operative to move said key carrying members.

108. In a typewriting or like machine, the combination of a keyboard, printing instrumentalities controlled by the keys thereof, means which enable the keys of the key-

board to slide fore and aft of the machine from their operative position in the keyboard to a contracted relationship nearer to the rear of the machine than when said keys are in position for use.

70

109. The combination of a machine-frame in which is included a main section on which a platen is supported, type bars, a keyboard in which printing keys are included, and means which enable said keyboard to be shifted into and out of said main section while the printing keys remain in upright uninverted positions.

110. The combination of a machine frame in which is included a main or base section on which a platen is supported, pivoted type bars, a keyboard in which printing keys are included, separate and distinct actuating connections between each printing key and a type bar, and means which enable said keyboard to be shifted from its position of use into said main or base section to reduce the dimensions of the machine.

80

111. The combination of printing instrumentalities, a keyboard in which printing keys and a space key are included, means which enable the keyboard to be displaced to a more compact position, and means which enable the space key to be displaced to a more compact position relatively to said printing keys.

90

112. The combination of printing instrumentalities, a series of keys therefor and which go to make up the keyboard of the machine, a main body portion of the frame of the machine, and means which enable said keyboard to be displaced relatively to said main body portion of the frame and into closer relationship therewith while the keys are maintained in upright positions, whereby the dimensions of the machine may be reduced without inverting the keys.

105

113. In a typewriting machine, the combination of a platen; type carriers; keys therefor; means for enabling said keys to be shifted into and out of a position for use; and means for enabling a relative displacement to be effected between the type carriers and platen into and out of position for use so that the machine will occupy a smaller space than it occupies when in use.

110

114. In a typewriting machine, the combination of a platen, type carriers, a keyboard, and means which enable the machine to be contracted into a smaller space than it occupies when in use, said means comprising means which enable the keyboard to be shifted out of position of use and the relation between the type carriers and platen to be changed automatically, the automatic change being dependent on the shifting of the keyboard as specified.

120

115. In a typewriting machine, the combination of type bars, a platen, and means for reducing the dimensions of the machine,

130

which means comprises means for simultaneously moving all of the type bars of the system to an inoperative position and relatively to the platen.

- 5 116. In a typewriting machine, the combination of a series of pivoted type bars mounted in an arc to strike at a common center, a machine frame comprising a plurality of sections connected for relative 10 movement one on another, a platen carried by one of said sections, a keyboard in which a series of printing keys is included, separate and distinct mechanical actuating connections between each printing key and its 15 type bar, and means which enable said keyboard to be moved into and out of that frame section which carries the platen, whereby the machine may be collapsed and its dimensions reduced.
- 20 117. In a typewriting machine, the combination of a keyboard in which a group of printing keys and a space key are included; and means for enabling the machine to occupy a smaller space than when it is in use, 25 said means comprising means for enabling the space key and group of printing keys to receive a relative shifting movement into and out of close relationship while they are maintained upright as in condition for use.
- 30 118. In a typewriting machine, the combination of a platen; pivoted type bars; a

keyboard in which printing keys are included; actuating connections between said printing keys and type bars; and means which enable the machine to occupy less 35 space than when it is in use, the same comprising means which enable the keyboard and type bars to be shifted closer to the platen.

119. In a typewriting machine, the combination with a keyboard comprising printing keys and a space key, of means for affording a relative movement between the space key and printing keys which enables the space key to be brought beneath certain 45 of said printing keys.

120. In a typewriting machine, the combination with a keyboard comprising banks of printing keys and a space key, of means for affording a relative fore and aft movement between the space key and printing keys which enables the space key to be brought beneath the first bank of printing keys.

Signed at Charlestown, in the county of 55 Suffolk, and State of Massachusetts, this twenty first day of September A. D. 1915.

PHILIPPE DE CLAMECY.
